UNITED STATES PATENT OFFICE.

WILLIAM HENRY HARRINGTON, OF HARTFORD, CONNECTICUT, ASSIGNOR TO THE ARROW ELECTRIC COMPANY, OF HARTFORD, CONNECTICUT, A CORPORATION OF CONNECTICUT.

DESIGN FOR AN ATTACHMENT-PLUG OR CONNECTOR.

59,840.

Specification for Design.

Patented Nov. 29, 1921.

Application filed June 25, 1921. Serial No. 480,454. Term of patent 14 years.

To all whom it may concern:

Be it known that I, WILLIAM HENRY HARRINGTON, a citizen of the United States of America, residing at Hartford, in the county of Hartford and State of Connecticut, have invented a new, original, and ornamental Design for Attachment-Plugs or Connectors, of which the following is a specification, reference being had to the accompanying drawing, forming part thereof.

Figure 1 is a side elevation of an attachment plug or connector, showing my new design;

Fig. 2 is a similar view at right angles; and

Fig. 3 is an end view thereof.

With reference to Fig. 3, it is pointed out that while I wish to show two holes in the end of the plug, the particular shape of these holes does not enter into my design. Thus, instead of being circular as indicated, they may be elliptical, rectangular, or other shape, without affecting the main outlines of the design to which my invention is directed.

I claim:—

The ornamental design for an attachment plug or connector, as shown.

WILLIAM HENRY HARRINGTON.
